BLACK-OUT LAMP

John Philip Todd, Mamaroneck, N. Y.

Application February 5, 1942, Serial No. 429,592

4 Claims. (Cl. 240—108)

In times of war, which involves the bombing of municipalities especially at night by enemy aeroplanes flying overhead, it becomes necessary as a defense measure to extinguish all lights by which the enemy aeroplane may be guided and its target ascertained and this necessitates not only the extinguishment of all street and other outside lights but also either the extinguishment of lights within houses and other buildings or the masking of all windows with opaque material to prevent the escape of light from the inside. Such measures are known as a "black-out."

Since a complete black-out involves all the dangers attendant upon the movement of pedestrians and vehicles in total darkness, such as injuries resulting from collision, and is furthermore conducive to crime, and since the masking of windows in homes, workshops and other buildings in order that lights may be used therein so that those inside may move about with safety and efficiency, is an expensive and burdensome task, which it is difficult to perform in the necessarily short space of time available after warning has been received of the approach of enemy aeroplanes, it is one of the objects of my invention to provide a lamp whereby objects in the immediate vicinity of such lamp, for instance, furniture in a room, may be sufficiently illuminated to enable one to see and move about without colliding with said objects or furniture and yet from a short distance away from said lamp, such as, from the street, 25 or 30 feet distant from the house, the room appears through an open window to be absolutely dark with nothing visible therein.

A further object of my invention is to provide a lamp in which the light proceeding therefrom is so thoroughly diffused that it forms no defined beam or cone. A still further object of my invention is to provide a lamp that consists of but few parts which may be readily assembled at small cost.

Other and further objects and advantages of my invention may be understood from the following description of it taken in connection with the appended drawing in which

Fig. 1 is a longitudinal cross-section of the lamp of my invention, and

Fig. 2 is a view on the line 2—2 of Fig. 1.

Referring to the drawing, 10 is a round shade of conical shape and preferably of a size about 3½ inches in diameter at its bottom, about 2½ inches in diameter at its top and about 6 inches in length. Said shade is open at the bottom

and closed against the escape of light at the top. In the top is rigidly mounted the lamp socket 11 having a screw base 12 extending through the top so that it is adaptable for insertion in the ordinary lamp socket. Inserted in the socket 11 is a frosted lamp bulb 13 of a capacity of preferably about 50 watts. The inside surface of the shade 10 may be of bright metal or painted white or otherwise treated to render it light reflecting.

10 Towards the other end of said shade is a circular screen 14. Said screen is preferably composed of wire cloth having square meshes of about 16 to the inch, i. e. 256 to the square inch.

15 Immediately below the screen 14 and surrounding the inner surface of the shade 10 is a spacing ring 15 about one-half inch in height formed with a plurality of closely spaced inwardly projecting triangular tongues 16. Said tongues are 20 each formed by cutting said ring from the bottom along one side 17 of a right-angle isosceles triangle and bending said tongues inwardly along the line of the other side 18 of said triangle to the extent of about 45° angular displacement 25 from the surface of said spacing ring. The right angle of the said triangle constitutes its apex which is located about one-quarter of an inch from the bottom of said spacing ring. Said tongues are made of bright metal or are otherwise rendered light reflecting on their upper side. It will be seen that the planes of said tongues are thus disposed at an interior angle of 45° to the cross-sectional plane of said ring.

30 Positioned immediately below said spacing ring 15 is a circular plate of thick translucent diffusive glass 19 of a color of relatively low visibility, preferably of a blue color, having an irregular surface and known as cathedral blue streaked hammered pattern glass having an irregular wavy surface.

35 Positioned immediately below said glass is a round disc 20 perforated with a plurality of round holes 21 distributed substantially regularly over the surface thereof. I find that holes having a diameter of about one-sixteenth of an inch and disposed at a frequency of about 25 to the square inch to be eminently satisfactory. Said disc may be flat but I find that I get better results by having it dished inwardly as shown. Said disc is 40 held within the shade 10 by the bent-over portions 22 of said shade and acts as a support for the glass 19, the spacing ring 15 and the screen 14 above it, or the said screen, tongues, glass and disc may be assembled and mounted within a 45 circular frame with the said tongues occupying

the same relative position intermediate the screen and the glass and held within the open end of the shade in any convenient manner.

It is to be understood that the screen, glass and disc completely fill the cross-sectional areas of the shade 10 at their respective levels so that no light proceeds from the shade except through the said screen, spacing ring, glass and disc, and are disposed at right angles to the axis of the shade 10.

Said tongues act as reflecting baffles causing the rays which would otherwise strike the glass 19 adjacent its margin in a more or less perpendicular direction, to be reflected either away from said glass or to enter it at a wide angle of incidence, thus increasing the diffused character of the light emerging through the holes 21 in the disc 20 and broadening the angular distribution of said diffused light. This may not be all the functions of the said tongues but I find by experiment that with the tongues formed in the spacing ring 15 comprising part of the assembly as shown, the illumination of objects in a room is better and renders them more distinct than if such tongues were omitted, and at the same time their presence does not lessen the invisibility of those objects from the same distance outside the house.

With a lamp of the size and characteristics above described hung from the center of the ceiling at a convenient height in a living-room 15 by 25 feet in dimension, the said lamp furnishes sufficient light on a dark night to easily distinguish all objects in the room and, in fact, to read a newspaper close to and directly under it, while at a distance from 25 to 30 feet away on the outside the room appears as totally dark with no objects visible to a person looking in through an open window, and where there is no direct view of the disc 20 the lamp itself is also invisible.

The foregoing is a description of one embodiment of my invention, which is subject to changes and adaptations for other uses, for instance, automobile lights and street lighting, without departing from the spirit of my invention as defined in the appended claims.

What I claim is:

1. A lamp comprising an opaque shade, a lamp bulb mounted therein, means for filtering said light so as to permit the passage therefrom of light of a color of low visibility only and for diffusing said light, a wire mesh screen positioned between and spaced apart from both said lamp bulb and said light diffusing and filtering means

and a perforated disc positioned on the outside of said light diffusing and filtering means.

2. A black-out lamp comprising an opaque conical lampshade having one end open for the passage of light, a lamp bulb mounted in the other end of said shade, a wire cloth having 16 square meshes to the inch, a spacing ring formed with a plurality of inwardly projecting triangular tongues arranged close together about the inside circumference of said spacing ring, the surface of said tongues being light reflecting and the plane of said tongues being disposed at an angle of substantially 45° to the cross-sectional plane of said ring, a sheet of cathedral blue streaked hammered pattern glass and a disc formed with a plurality of small, closely spaced perforations therein, said wire cloth, spacing ring, glass and disc being positioned within said shade in the order named adjacent the open end of said shade.

3. A lamp comprising an opaque lampshade having one end open for the passage of light, a lamp bulb mounted in the other end of said shade, a wire cloth having about 16 square meshes to the inch, a spacing ring formed with a plurality of inwardly projecting triangular tongues arranged close together about the inside circumference of said spacing ring, the surface of said tongues being light reflecting and the plane of said tongues being disposed at an angle of substantially 45° to the cross-sectional plane of said ring, a sheet of cathedral blue streaked hammered pattern glass and a disc formed with a plurality of small, closely spaced perforations therein, said wire cloth, spacing ring, glass and disc being positioned within said shade in the order named adjacent the open end of said shade.

4. A lamp comprising an opaque lampshade having one end open for the passage of light, a lamp bulb mounted in the other end of said shade, a wire cloth having about 16 square meshes to the inch, a spacing ring formed with a plurality of inwardly projecting triangular tongues arranged close together about the inside circumference of said spacing ring, the surface of said tongues being light reflecting and the plane of said tongues being disposed at an angle of substantially 45° to the cross-sectional plane of said ring, a sheet of translucent glass of a color of relatively low visibility and a disc formed with a plurality of small, closely spaced perforations therein, said wire cloth, spacing ring, glass and disc being positioned within said shade in the order named adjacent the open end of said shade.

JOHN PHILIP TODD.
